UNITED STATES PATENT OFFICE.

JASPER VANNETTE, OF TIFFIN, OHIO.

SEWING-MACHINE.

No. 813,929.

Specification of Letters Patent.

Patented Feb. 27, 1906.

Application filed August 11, 1898. Serial No. 688,393.

To all whom it may concern:

Be it known that I, JASPER VANNETTE, a citizen of the United States, residing at Tiffin, in the county of Seneca, State of Ohio, have invented certain new and useful Improvements in Sewing-Machines, of which the following description, taken in connection with the drawings herewith accompanying, is a specification.

- 10. This invention relates to sewing-machines, and more particularly to lock-stitch sewing-machines of that class in which both the upper and under thread are taken direct from the ordinary commercial spool of sewing-thread, the advantages offered by such class of machines being that a greater supply of under thread is provided than that afforded by the ordinary bobbin, whereby the machine may be run longer without stopping for a new
- 15. thread-supply and also the trouble and loss of time attendant upon winding the bobbin is avoided.

My invention has for its object to improve machines of the class referred to by rendering the same capable of being operated at a greatly-increased speed, reducing noise and vibration, and otherwise rendering the same more effective and desirable than heretofore constructed.

- 20. In the accompanying drawings, in which I have illustrated only so much of a sewing-machine as is necessary to explain my invention, Figure 1 is a bottom view of a portion of the bed-plate of a sewing-machine with certain parts of a stitch-forming mechanism thereon embodying my invention. Fig. 2 is a longitudinal section through line 2 2 of the construction shown in Fig. 1. Fig. 3 is a detail view of certain of the parts shown in Fig. 2, showing the change in position of the same at a different time during the formation of a stitch. Fig. 4 is a front end view of the machine with certain of the parts removed and in section to more clearly show the reciprocally-moving spool-supporting frame, spool-driver, and loop-pusher and the connection between such parts. Fig. 5 is a detail view, partly in section, showing the relative positions assumed by the spool-supporting frame, spool, loop-spreader, and loop-seizing hook at a time when the latter first enters the thread-loop thrown out by the needle, the several parts being shown in elevation. Fig. 6 is a view similar to that of Fig. 5, showing the position assumed by the parts at a different time during the formation of a stitch.

Figs. 7 and 8 are plan views of the movable parts shown in Figs. 5 and 6 and the loop-pusher with certain of the parts in section and broken away, also showing different positions assumed by the parts during the formation of a stitch. Figs. 9 to 13, inclusive, are views illustrating the operation of certain of the moving parts in taking the thread-loop from the needle and passing it around the spool carrying the under thread, whereby it will interlock with the latter. Fig. 14 is a view of a spool-case embodying my invention. Figs. 15 and 16 are views illustrating modifications in the construction of certain of the parts to be hereinafter referred to, and Fig. 17 is a perspective view of the loop-seizing hook detached from its operating-shaft.

To explain in detail, *a* denotes the bed-plate of a sewing-machine, and *a'* the needle. I have not considered it necessary to illustrate any of the stitch-forming mechanism above the bed-plate other than the needle, as it may be of any well-known kind.

Beneath the bed-plate *a* is a spool-supporting frame *b*, which is adapted to be supported in any suitable manner to be capable of having a reciprocating movement, the same, as more clearly shown in Fig. 1, being provided with arms or extensions *b'*, which are loosely seated within openings formed in hangers *a'* *a'* on the under side of the bed-plate. This frame *b*, which may be of any suitable form, is provided with two pins or rods *b* *b*, arranged in line with each other, on which an ordinary commercial spool *b*, carrying the under-thread supply, is adapted to be loosely supported to have a reciprocating movement. A space or opening *b* is provided between the adjacent ends of the two pins *b* *b*, through which the needle-thread loop is passed by suitable means for the purpose of receiving the reciprocating spool *b* therethrough. After the spool has been passed through the needle-thread loop the latter is then drawn back through the opening between the pins by the ordinary take-up acting above the cloth-plate of the machine and caused to interlock with the under thread and form a lock-stitch in the usual manner. The spool *b*, which is preferably inclosed in a cylindrical case *h*, is reciprocated back and forth from one to the other of the rods *b* by means of a driver *c*. This driver, as herein shown, consists of a frame or plate *c'*, which is supported to slide in guideways *c* *c* in the spool-frame *b*, as more

clearly shown in Figs. 2 and 4, and provided with suitable arms c^3 c^4 for loosely engaging with the opposite ends of the spool. A rotating shaft d , supported in suitable bearings 5 on the under side of the bed-plate, is provided with a crank d' , which is connected, through the medium of a pitman d^2 , with a fixed pin c^5 on the spool-driver c , so as to communicate the desired movement to the latter. It will be understood that when one end of the spool b^3 has entered into the needle-thread loop which has been passed through the openings b^4 between the ends of the rods b^2 such needle-thread loop cannot be 10 drawn up by the take-up to complete the stitch until it has passed off the opposite end of the spool and is enabled to pass through the said opening b^4 between the ends of the rods b^2 . Therefore as an important feature 15 of my present invention I have arranged for reciprocating the spool-frame in opposition to the movement of the spool and its case, whereby the said opening b^4 of the spool-frame after receiving the needle-thread loop there- 20 through for the purpose of being passed around the front end of the spool will be moved toward the opposite end of the spool during the movement of the latter in the contrary direction, and thus enable the thread-loop to be drawn off the spool and through 25 the said opening b^4 in one-half the time that would be required in case of the individual movement of the spool alone. The spool-frame b receives its reciprocating movement 30 also from the rotating shaft d through the medium of a second crank d^3 , with which the latter is provided, and a pitman d^4 , connecting said crank with a pin b^6 on the spool-frame, as more clearly shown in Figs. 1 and 35 40. The movements of the spool-driver and the spool-frame in opposition to each other, as described, is secured by so arranging the two cranks d' and d^3 that the throw of one is opposite to the throw of the other. By reason 45 of such movement of both the spool-frame and spool-driver in opposition to each other the throw of movement of such parts for the purpose of passing the needle-thread loop around the under thread is only one- 50 half of that which would be required in case the movement was confined to one of the parts. I am thus enabled to employ easy crank or eccentric movements to operate the said parts, and so materially diminish noise, 55 vibration, and friction, as well as increase the durability and general effectiveness of the machine.

The body portion of the spool-frame b , within which the spool-driver is supported to 60 slide, is provided with a central elongated opening b^7 therein, through which the crank-shaft d extends, as more clearly shown in Fig. 2, whereby a direct line of draft is secured between the cranks d' and d^3 and the 65 pitman-connected spool-driver and spool-

frame. The said cranks being located at that side of the spool-frame b opposite the spool also prevents possibility of the ends of the thread from either the upper or lower spool coming in contact with the same and 70 getting entangled therewith.

The means for taking the thread-loop thrown out by the needle and passing the same around one end of the spool b^3 consists of a loop-seizing hook e , which first enters the 75 needle-thread loop and opens the same, and a loop-spreading finger f , which engages with one side of the opened loop and then, acting in combination with the hook e , spreads the loop through the opening b^4 of the spool-frame and around the end of the spool. The hook e , which is carried at the front end of a rotating shaft e' , mounted in suitable bearings on the under side of the bed-plate, is formed with an attaching-shank e^2 , having a 80 substantially triangular shaped loop-seizing blade e^3 at one side thereof, which is pointed at its front end and tapered to considerable width at its rear end. This form of blade insures the ready entry of the same into the 85 needle-thread loop and after receiving a partial turn, as shown in Fig. 6, opens the loop to considerable width and causes the same to assume a well-defined triangular shape with the forward or upper side thereof in the path 90 of the loop-spreader f , which latter moves forward at such time in a path at right angles to the path of the loop-seizing hook and engages with the said upper side of the loop, as shown in Figs. 2 and 11, and carries the 95 same over and across one end of the spool and through the opening b^4 of the spool-frame. This loop-spreader moves in a substantially circular path around the spool-case, and as it 100 engages one side of the loop and carries it over and across the end of the spool the hook 105 e , with its engaging portion of the loop, continues its downward movement in a path parallel with one side of the spool, and so acts in combination with the loop-spreader to 110 pass the loop around the end of the spool, whereby the latter may be passed through the same.

The detailed operation of the parts in taking the needle-thread loop from the needle 115 and passing it around the spool, as illustrated in the drawings, is as follows: The loop-seizing blade first enters the needle-thread loop thrown out by the needle, as shown in Figs. 5 and 9, and after fully entering the same 120 causes the thread-loop to receive a partial turn as one side thereof passes around to the rear end of the blade, as in Fig. 10, whereby the sides of the loop will be operated apart in a direction at right angles to the path of the 125 loop-spreader. Continuing its movement, the loop-seizing blade causes the loop to assume a triangular shape with the sides widely separated and the upper side in the path of the loop-spreader, which now advances to 130

- engage the same, as in Fig. 6. The sides of the loop being thus widely separated permits the use of a long thread-engaging finger f' on the loop-spreader, which may engage 5 with one side of the loop without liability of striking the other and extend a considerable distance over the end of the spool to insure the thread being carried thereover. After the parts have reached the position shown in 10 Fig. 6 the loop-spreader continues to move forward and the loop - seizing hook downward, as shown in Fig. 11, until they reach the position shown in Fig. 7, at which time the spreader has carried one side of the loop 15 from the needle-opening over the upper side of the spool, while the spreader and hook together have carried the intermediate portion of the loop across the end of the spool through the opening b^4 of the spool-frame. The continued movement of the parts, as shown in 20 Fig. 12, carries the lower portion of the loop between the adjacent arm c^3 of the spool-driver and the end of the spool, and so completes the encircling of the latter by the loop. 25 During such action of the parts in passing the thread-loop around the end of the spool the spool-frame and spool are being moved in opposition to each other, the timing of the parts being such that as soon as the loop is carried 30 through the opening b^4 of the spool-frame the spool moves across such opening. When the parts reach the position shown in Fig. 8, with the opening b^4 of the spool-frame at the opposite end of the spool, the loop has also been 35 moved to such position by the action of the loop-seizing hook e moving in a direction contrary to the movement of the spool and is free to be drawn up by the usual take-up to interlock with the under thread, as shown in 40 Figs. 8 and 13, and complete the stitch. 45 The particular form of the loop - seizing hook as described enables the same to enter the thread-loop as it is thrown out by the needle and continue its movement without requiring additional slack thread until the blade e^3 has fully entered the loop and the latter has passed around to the rear end of the blade, during which time the needle has moved above the work being operated upon, 50 as shown in Fig. 10. The advantage secured by such action of the parts is that the hole made in the goods by the passage of the needle therethrough is not obstructed by the presence of the needle when the thread is being drawn through said hole by the hook e , 55 thus reducing the friction on the needle-thread.
- Any suitable means may be employed for acting in combination with the loop-seizing 60 hook to engage with one side of the loop and carry the same across the end of the spool and around its inclosing case, as described. The loop-spreader, as herein shown, consists of the thread-engaging finger f' , which is carried at one end of a lever f^2 , the latter being 65 pivotally connected at its opposite end to a vertically-disposed lever f^3 , which is fulcrumed on a lug f^4 on the under side of the bed-plate and provided with a pin having an antifriction-roll f^5 thereon, which extends 70 within a cam-groove f^6 , formed in a sleeve which is secured on the shaft d . This cam f^6 imparts a horizontally-reciprocating movement to the lever f^2 . An elbow-lever f^7 , fulcrumed on a lug f^8 on the under side of the 75 bed-plate, is provided with a stud f^9 on one arm, extending into a longitudinal slot f^{10} in the lever f^2 and with a connected antifriction-roll f^{11} on the other arm extending into a cam-groove f^{12} , formed in a sleeve which is 80 also secured on a rotating shaft d . This lever f^7 is operated to communicate a vertical movement to the lever f^2 and, acting in combination with the lever f^3 , causes the thread-engaging finger f' of the lever f^2 to move in a 85 substantially circular path around the spool-case and inclosed spool, the position assumed by the parts at different times in their operation being shown in Figs. 2 and 3.
- As before described, the loop-seizing hook 90 e moves in a path at one side of the path of the reciprocating spool and after the thread-loop has been passed around one end of said spool carries the loop to the opposite end of the latter and in position to be drawn up by 95 the take-up through the opening b^4 of the spool-frame. The thread-loop in being carried longitudinally over the spool-case is thus acted upon only at one side of the latter, and consequently would cause that portion 100 at the opposite side of the spool-case to drag. To prevent such drag and insure the more positive and rapid action of the loop in being passed longitudinally over the case h , I employ a loop-pusher for engaging with the loop 105 on that side of the case opposite the hook e and pushing the same in a direction in opposition to the movement of the spool, whereby the loop will be directly engaged at opposite sides of the case and positively carried from 110 one end of the latter to the other. The loop-pusher, as more clearly shown in Figs. 2, 7, and 8, consists of a plate i , which is movably supported on the spool-frame with one edge thereof extending into a longitudinal open 115 slot h' in one side of the spool-case h and provided with a notch i' in such edge, which permits of the passage of the loop-spreader therethrough in carrying the loop around the end of the spool and also forms a shoulder i^2 , 120 which is adapted to engage with the side of the encircling loop, as shown in Fig. 12, and, moving in the same direction with the spool-frame and in opposition to the movement of the spool, push said loop to the opposite end 125 of the spool-case and off the same, as shown in Fig. 8. The edge of the plate i extending into the slot h' of the spool-case prevents rocking movement of the latter with its inclosed spool and also positively insures the 130

engagement of the thread-engaging shoulder i^2 with the thread-loop which has been carried across the said slot, as shown. When the loop-pusher is movably supported on the 5 spool-frame, it is connected with the latter to be operated thereby through the medium of toggle-links i^3 i^3 , which are centrally supported and controlled by a connecting-link i^4 , which is pivotally connected with a fixed 10 support i^5 on the under side of the bed-plate. Such connection secures a differential movement of the loop-pusher relative to the spool-frame, whereby the former is caused to move faster than the latter during such time as it 15 is pushing the thread-loop, so as to insure the latter being pushed off the end of the spool-case and drawn up through the opening b^4 of the spool-frame before such opening is closed by being entered into the spool. The loop-pusher may, however, be formed as an integral part of the spool-frame, as shown in Fig. 16, or be otherwise constructed and supported to properly perform its function, as described, without departure from my invention. 20

To provide for placing the spool in position upon the rods b^2 of the spool-frame or removing it therefrom, one of said rods has a screw-threaded connection with the frame, as 30 shown, whereby it may be moved to increase the space between the ends of the said rods sufficiently to permit of the spool being readily slipped on or off the same. Such movable rod has a crank-handle b^9 as a means for 35 operating the same.

The wooden spool b^3 is adapted to ride directly upon the rods b^2 without any intermediate support, as I find that the friction caused by lint, dust, or other foreign matter 40 getting between such parts has no appreciable effect upon the action of the same, as it does in the case of a metallic support for the spool riding upon said rods. The spool, being supported in such manner, also permits 45 the spool-case being made very cheap, simple, and light, the same being preferably formed of a simple piece of sheet metal bent into a substantially cylindrical form, as shown. This case is adapted to be supported 50 upon the peripheries of the end flanges on the spool and be retained in position against undue endwise movement thereon by means of the arms c^3 c^4 of the spool-driver, engaging the opposite ends of the same. Rocking or 55 turning of the spool-case h , as before described, is prevented by means of the loop-pusher i extending into the open slot h' , with which said case is provided. In lieu of such slot in the spool-case, however, the latter 60 might be provided with a tongue h^3 thereon and the edge of the loop-pusher be provided with a groove h^4 to receive said tongue, as shown in Fig. 15. Such a construction would accomplish the same purpose as the 65 construction first described. The space be-

tween the opposite ends or arms c^3 c^4 of the spool-driver is of course greater than the length of the spool-case, so as to permit of the needle-thread loop being readily passed between such arms and the adjacent ends of the case when the latter, with its inclosed 70 spool, is being passed through said thread-loop. The rear arm c^4 of the spool-driver extends upward across the center of the spool b^3 and is provided with an opening c^8 therein, 75 which receives the rods b^2 of the spool-frame, and is also adapted to permit the thread-loop being drawn upward by the take-up without liability of getting caught between the end of one of the rods b^2 and the said arm c^4 , as will 80 be obvious upon reference to Fig. 8. The spool-case may be provided with any suitable means for giving the desired tension to the under thread, the same, as herein shown, being formed with a series of arms h^5 , over 85 and under which the thread is passed, as shown in Fig. 14. The case h is also provided with a number of slots or openings, as shown, adapted to lighten the same and also permit the operator to see the inclosed spool 90 for the purpose of ascertaining from time to time the amount of thread remaining on the spool.

In order to provide a simple and practical means whereby the different makes, kinds, 95 sizes, and numbers of commercial spools of sewing-thread, which vary more or less in size, may be used in the machine by the ordinary operator, I provide a series of cases, each being provided with the proper indicative numbers or characters stamped or otherwise located thereon to denote the one or more kinds of thread which it may be adapted to contain. For instance, the case illustrated in Figs. 4, 5, and 6 and marked "A, B, 100 D silk" indicates that such case is adapted to inclose commercial spools of sewing-silk of the three numbers indicated. The several spool-cases are adapted to the particular sizes and numbers of the spools of thread 105 which they are intended to inclose by having their inner diameter and length of the proper size to contain the particular spool without undue movement of the latter therein. For instance, a case intended to inclose a "No. 70 110 cotton," as in Fig. 14, is reduced both in diameter and length to correspond to such size of spool, the length being regulated by providing the case with an inwardly-projecting shoulder h^7 , it being understood that the 115 length of the several cases are uniform to properly fit between the engaging ends or arms of the spool-driver.

Having thus illustrated and described a practical embodiment of my invention, it will 120 be obvious that the same may be more or less materially modified without departure from the spirit of the invention, also in lieu of the commercial spool for carrying the under thread as described an ordinary bobbin 125 130

wound in the usual manner might be employed, and I wish it to be understood that the term "spool" as used throughout the specification and claims unless otherwise defined is intended to cover a bobbin or any other similar thread-carrying device.

What I claim as my invention, and desire to secure by Letters Patent, is—

1. In a sewing-machine, the combination, with the needle and its operating mechanism, of a spool carrying the under thread, a reciprocally-moving frame supporting said spool and having an opening of less length than the latter for the passage of the needle-thread loop in being passed around the spool, the position of said opening being shifted from one end to the other of the spool by the movement of the frame, and means for taking the thread-loop from the needle and passing it around said spool to interlock with the thread carried thereby, said means including a loop-seizing hook and a loop-spreader, the latter being independent of the hook and movable in a path through the said opening in the spool-frame.

2. In a sewing-machine, the combination, with the needle and its operating mechanism, of a spool carrying the under thread, a case inclosing said spool, a reciprocally-moving frame supporting said spool and case and having an opening for the passage of the needle-thread loop in being passed around the spool, the position of said opening being shifted from one end to the other of the spool by the movement of the frame, and means for taking the thread-loop from the needle and passing it around said spool to interlock with the thread carried thereby, said means including a loop-seizing hook and a loop-spreader, the latter being independent of the hook and movable in a path through the said opening in the spool-frame.

3. In a sewing-machine, the combination, with the needle and its operating mechanism, of a spool carrying the under thread, a frame supporting said spool and having an opening for the passage therethrough of the needle-thread loop, means for imparting movement to said spool and spool-frame in a direction in opposition to each other, and means for passing a needle-thread loop through said opening in the spool-frame and around the spool.

4. In a sewing-machine, the combination, with the needle and its operating mechanism, of a spool carrying the under thread, a reciprocally-moving frame supporting said spool and having an opening for the passage therethrough of the needle-thread loop, a reciprocally-moving spool-driver operating in a direction in opposition to the movements of the spool-frame, and means for passing a needle-thread loop around the spool.

5. In a sewing-machine, the combination, with the needle and its operating mechani-

ism, of a spool carrying the under thread, a reciprocally-moving frame supporting said spool, a reciprocally-moving driver for imparting movement to the spool in a direction in opposition to the movements of the spool-frame, said driver being connected with the latter to be supported and guided thereby, and means for passing a needle-thread loop around the spool.

6. In a sewing-machine, the combination, with the needle and its operating mechanism, of a spool carrying the under thread, a frame supporting said spool provided with an opening for the passage of the needle-thread loop and also having guideways, a reciprocally-moving spool-driver supported and operating in said guideways in the spool-frame, and means for passing a needle-thread around the spool.

7. In a sewing-machine, the combination, with the needle and its operating mechanism, of a spool carrying the under thread, a reciprocally-moving frame supporting said spool and having an opening for the passage of the needle-thread loop, a loop-seizing hook operating in a path at one side of the spool-frame, a loop-spreader coöperating with said hook and moving in a path through said opening in the spool-frame to pass a needle-thread loop around the spool, means for operating said hook and loop-spreader, an operating-shaft having a crank or eccentric at that side of the frame opposite the hook, and means operatively connecting said crank or eccentric with the spool-frame.

8. In a sewing-machine, the combination, with the needle and its operating mechanism, of a spool carrying the under thread, a reciprocally-moving frame supporting said spool, a reciprocally-moving driver operating said spool in a direction in opposition to the movements of the frame, said driver having a part thereof provided with an opening to receive the spool-supporting portion of the spool-frame, and means for passing a needle-thread loop around the spool.

9. In a sewing-machine, the combination, with the needle and its operating mechanism, of a spool carrying the under thread, a support for said spool, a loop-seizing hook operating in a circular path at one side of said spool, a loop-spreader operating in a circular path at substantially right angles to the path of the hook and coöperating with the latter in passing the needle-thread around the spool, the thread engaging or drawing surface of the hook being arranged in a plane parallel with the plane of the path of movement of the hook, and means for operating said hook and spreader, respectively.

10. In a sewing-machine, the combination, with the needle and its operating mechanism, of a reciprocally-moving spool carrying the under thread, a support for said spool, a rotating loop-seizing hook having a relatively

- thin blade portion of substantially triangular form in a plane at right angles to its axis and provided with a thread-engaging surface at the rear end of said blade arranged in a 5 plane parallel with the plane of the path of movement of the hook and of the needle, the lower edge of said blade being arranged to move, during its passage through the needle-thread loop, in a path in line with or above 10 the lowest limit of movement of the needle-eye for the purpose set forth, and an independent loop-spreader coöperating with said hook in passing the needle-thread around the under thread.
- 15 11. In a sewing-machine, the combination, with the needle and its operating mechanism, of a spool carrying the under-thread supply, a rotating shaft carrying a loop-seizing hook, said hook being provided with a thread-engaging surface arranged at right angles to the axis of its operating-shaft whereby the sides of an engaged needle - thread loop will be opened or spread apart in a direction parallel with the plane of the path of movement of the 20 hook, a loop-spreader moving in a path to engage one side of said opened loop and carry the same around the spool, and means for operating said loop-spreader.
12. In a sewing-machine, the combination, 30 with the needle and its operating mechanism, of a spool carrying the under-thread supply, a frame supporting said spool, a circularly-moving loop-seizing hook operating in a path parallel with one side of the spool, a circularly-moving loop-spreader operating in a path around the spool, and means for operating the said hook and spreader, respectively.
13. In a sewing-machine, the combination, 40 with the needle and its operating mechanism, of a reciprocally-moving spool carrying the under thread, a rotating loop - seizing hook having a relatively wide thread - engaging surface arranged at right angles to its axis for entering and opening the needle-thread 45 loop into a triangular shape with the sides spread apart in the direction of movement of the hook, a loop-spreader moving in a path to engage one side of the opened loop and 50 carry the same around the spool, and means for operating the hook and spreader, respectively.
14. In a sewing-machine, the combination, 55 with the needle and its operating mechanism, of a spool carrying the under thread, a reciprocally-moving frame supporting said spool and having an opening for the passage of the needle-thread loop, a loop-seizing hook moving 60 in a circular path at one side of said spool, a loop-spreader moving in a circular path around one end of the latter and coöperating with the hook in passing a needle-thread loop around the same, and means for operating the 65 said hook and spreader, respectively.
15. In a sewing-machine, the combination, 70 with the needle and its operating mechanism, of a spool carrying the under thread, a support for said spool, a loop-seizing hook and its operating mechanism, a circularly-moving loop-spreader coöperating with said hook in passing the needle - thread around the spool, consisting of a lever having means at its front end for engaging with the thread, a vibrating lever connecting with the rear end of said spreader-lever, and means, coöperating 75 with said vibrating lever, to impart a circular movement to the thread-engaging end of the spreader-lever.
16. In a sewing-machine, the combination, 80 with the needle and its operating mechanism, of a spool carrying the under thread, a reciprocally-moving frame supporting said spool and having an opening in its spool-supporting portion, a circularly-moving loop-seizing hook operating in a path at one side of the 85 spool, a loop-spreader, consisting of a lever having a thread-engaging arm, and means for moving said lever through the said opening of the spool-frame and causing its thread-engaging arm to move in a circular path 90 around the end of the spool.
17. In a sewing-machine, the combination, 95 with the needle and its operating mechanism, of a spool carrying the under thread, a support for said spool, a loop-seizing hook and its operating mechanism, a loop-spreader for coöperating with said hook in passing a thread-loop around the spool, consisting of a lever having a thread-engaging portion, a vibrating lever pivotally connected with one 100 end of said spreader-lever, and a second vibrating lever having a sliding connection with the spreader-lever and coöperating with the first lever in imparting a circular movement to the thread-engaging end or portion 105 of said spreader-lever.
18. In a sewing-machine, the combination, 110 with the needle and its operating mechanism, of a spool carrying the under thread, means for passing the needle - thread loop around one end of said spool, and a reciprocally-moving loop-pusher operating in a path at one side of the spool for pushing the thread-loop along the same.
19. In a sewing-machine, the combination, 115 with the needle and its operating mechanism, of a spool carrying the under thread, a case inclosing said spool, means for passing the needle-thread loop around one end of said spool, and a reciprocally-moving loop-pusher 120 operating in a path at one side of the spool and having a loose connection with the spool-case.
20. In a sewing-machine, the combination, 125 with the needle and its operating mechanism, of a spool carrying the under thread, a case inclosing said spool and having a slot therein, means for passing the needle - thread loop around one end of said spool, and a reciprocally-moving loop-pusher operating in a path 130

- at one side of the spool with one edge thereof extending into said slot in the spool-case.
21. In a sewing-machine, the combination, with the needle and its operating mechanism, of a reciprocally-moving spool carrying the under thread, a cylindrical case inclosing said spool, means for passing the needle-thread loop around one end of said spool-case, a loop-pusher operating in a path at one side of the spool for pushing the thread-loop along the latter, and means for imparting a reciprocating movement to the loop-pusher in opposition to the movements of the spool.
22. In a sewing-machine, the combination, with the needle and its operating mechanism, of a spool carrying the under thread, a case inclosing said spool, a reciprocally-moving frame supporting said spool and case and having an opening for the passage of the needle-thread loop, means for passing the needle-thread loop around one end of said spool-case, and a loop-pusher carried by said spool-frame for pushing the thread-loop along the spool-case.
23. In a sewing-machine, the combination, with the needle and its operating mechanism, of a reciprocally-moving spool carrying the under thread, a case inclosing said spool, means for passing the needle-thread loop around one end of said spool-case, a loop-pusher, consisting of a plate supported with one edge thereof loosely engaging with the spool-case to hold the latter from turning, and provided with a notch in that edge thereof adjacent to the spool-case forming a thread-engaging shoulder, and means for imparting a reciprocating movement to the loop-pusher in opposition to the movements of the spool.
24. In a sewing-machine, the combination, with the needle and its operating mechanism, of a spool carrying the under thread, a support for the spool, a case inclosing said spool provided with an open slot extending lengthwise through the same, means located exteriorly of said case and extending loosely into its slot so as to prevent a turning or rocking movement of the case with its inclosed spool, and means for passing a needle-thread loop around the spool and spool-case to interlock with the under thread.
25. In a sewing-machine, the combination, with the needle and its operating mechanism, of a commercial spool carrying the under thread, a support for said spool, a cylindrical case supported directly upon the periphery of the end flanges of the spool and having a stop projection located on its inner wall at a point distant from the end of the case so as to engage with a spool of less length than the latter and prevent undue endwise movement of the same, and means for passing a needle-thread loop around the spool and spool-case to interlock with the under thread.
26. In a sewing-machine, the combination, with a spool-supporting frame comprising two pins or rods, of a spool carrying the under thread riding directly upon said pins, an open-ended cylindrical case supported upon the periphery of the end flanges of the spool and means independent of the case for holding the same in longitudinal position upon the spool and communicating a reciprocating movement to the case and its inclosed spool.
